UNITED STATES PATENT OFFICE.

CARL J. HAZELTON, OF WORCESTER, MASSACHUSETTS, ASSIGNOR TO AMERICAN NARROW FABRIC COMPANY, OF WORCESTER, MASSACHUSETTS, A CORPORATION OF MASSACHUSETTS.

HOSE-SUPPORTER STRUCTURE.

Application filed September 3, 1926. Serial No. 133,331.

My invention relates to an improvement in hose supporter structures, and has particular reference to an improvement in the button and the base plate construction, whereby the button will at all times be securely held to the base plate without, however, employing holding devices such as rivets, for example, now commonly employed in this art.

10 One of the objects of my invention is the provision of a supporter structure which is so arranged that the button and base plate may be quickly assembled thereby reducing assembling costs as compared with the riveted form above referred to.

A still further object of my invention is the provision of a hose supporter structure in which the base plate is so constructed that the button may be said to be locked in place thereto, although, as above mentioned, my improved structure is entirely free from holding rivets or equivalent devices.

Another and further object of my invention is the provision of a hose supporter structure in which a two-section or two-piece base plate is employed which holds the button in place, the two sections of the base plate being interlocked if desired.

And still another object of my invention is the provision of a hose supporter structure employing a two-part or two-section base plate, into which the shank of the button is slipped, these two sections overlapping and if desired being locked to each other to provide in effect a single solid plate by which the button is securely held against displacement.

Other and further objects of my invention will appear hereinafter.

40 In the accompanying drawings, wherein I have illustrated an embodiment of my invention,

Fig. 1 shows the button and the two sections or parts of my improved structure in disassembled relation;

Fig. 2, which is a sectional view, shows the parts assembled; and

Fig. 3 shows a modification in disassembled relation.

50 Referring to the drawings in detail,

1 and 2 designate, respectively, what I will hereinafter refer to as the upper and lower base plate sections or parts. 3 designates the button which is to be held by the base plate.

55 The upper base plate section 1 is in the form of a thin metal plate of any suitable shape, and, as a matter of fact, of any suitable material. This plate is provided with two transverse web-receiving openings 4 and 5, these openings being adjacent the ends of the plate, and provided for the purpose of receiving the non-elastic of the supporter, as will be hereinafter pointed out.

60 Traversing the plate is an open-ended slot 6 which, as I will point out, receives the shank of the button 3, and consequently the shape and dimensions of this slot will depend upon the cross-section of the button shank. I have shown a rectangularly 65 shaped slot, but other non-circular shapes may be employed should such shapes be desirable. The button receiving slot 6 extends to the periphery of the plate and intersects the slot 4, the open end of the slot for 70 clarity of description being designated 7.

75 The lower base plate section 2 is a duplicate, in effect, of the upper section, being provided with transversely extending web-receiving slots 8 and 9 and with an open ended slot 10 intersecting the slot 9, the open end of this slot being designated 11, where the material at the end of the plate is cut through, this slot 10, as in the case 80 of the slot 6, extending to the periphery of 85 its base plate section.

85 The button 3 comprises a head 12, shank 13 and base 14. The head 12 may be of any desired shape, but as illustrated, is elongated, its long axis extending when the parts 90 are assembled, transversely of the supporter. The shank 13 is rectangular in section, corresponding in shape to the slots 6 and 10 which receive it, and is provided with a ridge or flash 13' on opposite sides thereof. 95 The base 14 is illustrated in the form of a flange 15, extending completely around the shank.

100 In assembling the base plate and button, the button shank 13 is slipped into the open end of the slot 10 in the lower base plate section until the front face of the shank 13 abuts the rear, closed end of the slot. The upper base plate section 1 is then slipped over the lower section, the shank 13 of the 105 button passing through the open end of the 110

slot 6, and into the slot 6 until the rear face of the shank abuts the closed end of the slot. The base 14 of the button underlies both base plate sections, extending beyond the sides of both slots 10 and 6, so that the button is prevented effectually from being lifted out of the base plate, and the ridges 13' are received by the slots 13" provided in the opposite walls of the open-ended slots 6 and 10.

Owing to the fact that the lower base plate section is slipped over the button in one direction and the upper plate in the opposite direction, the open end 7 of the slot 6 is closed by the plate 2, while the open end 11 of the slot 10 is closed by the plate 1, and as a consequence, movement of the button lengthwise of the base plate to escape from the slots is prevented. Movement of the two base plate sections relatively is prevented by providing the upper part 1 with projections 16, while the lower plate is provided with depressions 17, and when the parts are assembled the projections 16 are received by the depression as indicated in Fig. 2.

While I have just described means for preventing sliding of the sections 1 and 2 relatively to each other, such movement to a detrimental extent is prevented by the non-elastic 18. This non-elastic, after the button and base plate sections are assembled, is threaded down through the web-receiving openings 4 and 8 which at this time are in register with each other, as indicated at 19, then passed beneath the button and up through the openings 9 and 5, as indicated at 20, these openings now registering with each other. The non-elastic is then passed down beneath the button again as indicated at 21, the end turned over as indicated at 22 to provide a loop 23 and the two ends of the non-elastic stitched to each other as indicated at 24. This stitching 24 is practically directly at the end of the base plate sections, so that the base plate is firmly held.

It will be apparent from the foregoing, that the construction above described provides a supporter structure of simple construction and in which the button 3, which is a solid button, is held securely in position to the base plate without the use of rivets or similar securing devices.

It will be apparent also that I have provided a base plate structure which is so constructed that while the button may be slipped in place therein readily enough, it is effectually prevented from pulling out.

In the embodiment of my invention illustrated in Fig. 3 I have modified the construction of the base plate sections 1 and 2, the button in this embodiment of the invention, however, remaining unchanged. Referring to this figure of the drawings, 25 designates the upper section of my im-

proved base plate and 26 the lower section, while the button itself is designated 27. The base plate section 25 is provided at each end with web-receiving openings 28 and 29, and intermediate its ends with an open end 70 of the slot 30, which is of the proper dimensions to receive the shank 31 of the button 27. The slot 30 extends to the side of the plate and its open end has been designated 75 32. At the rear end, that is to say, at the end of this slot opposite the open end 32, a notch 33 is provided for receiving the ridge or flash 34 with which the base 35 of the button is provided. The base plate section 26 is similar in construction to the section just mentioned, being provided at each end with a web-receiving slot or opening, designated 36 and 37, respectively, while intermediate these two openings and cutting through the side of the plate is an 80 open-ended slot 38, the open end of which is designated 39 and the closed end of which is provided with a notch or slot 40 adapted to receive the ridge 34 above referred to. In assembling this structure, the plates 25 and 26 are pushed over the button shank laterally, and in superimposed relation, it being understood that when the parts are assembled the open ended slots 30 and 38 will extend in opposite directions, so that 85 the open end of one slot will be closed at the closed end of the other slot. The non-elastic used in connection with hose supporters has not been illustrated in connection with this figure, inasmuch as the same may be 90 threaded through the plate sections in a manner similar to that illustrated and described in connection with Fig. 2.

What I claim is:

1. A base plate structure for hose supporters comprising a pair of button-receiving plates, each plate being provided with an open-ended slot, and said plates being disposed so that said slots extend in opposite directions with the open end of the slot in 105 one plate closed by the material of the other plate adjacent the closed end of the slot in 110 the other plate.

2. A base plate structure for hose supporters comprising a pair of button-receiving plates, each plate being provided with an open-ended button-receiving slot, said plates being interlocked in superimposed position with the open end of the slot in one plate adjacent the closed end of the slot in 115 the other plate.

3. In a hose supporter structure, the combination of a button comprising a head, a shank and a base, a two-part or two-section base plate, each section of the base plate being provided with an open-ended slot, said plates being superimposed with said slots in register and extending in opposite 125 directions and with the shank of the button therein, the base of the button extending 130

beyond opposed portions of said slots, whereby the button is permanently held to both sections of the base plate.

4. In a hose supporter structure, the combination of a two-part base plate, each part or section of the base plate being provided with an open-ended slot extending to the periphery of the plate, a button comprising a head, a shank and a base, the two parts of the base plate being disposed in superimposed relation with the slot in each plate receiving the button shank, the base of the button extending beyond opposed portions of each slot, whereby the button is locked permanently to the plate.

5. In a hose supporter structure, the combination of a button comprising a solid head, shank and base, a two-part or two-section base plate, each section comprising a pair of web-receiving openings and an open-ended slot for receiving the button shank, each of said slots intersecting one of the web-receiving openings and extending to the periphery of the base plate section, the said plates being disposed in superimposed relation with the slots in the one plate section in register with the slots in the other section and with the open-ended slots extending in opposite directions, whereby the button is permanently attached to the two sections of the plate.

6. In a hose supporter, the combination of a button comprising a head, a shank and a base, a ridge on opposite faces of said shank, a two section base plate, each of said sec-

tions being provided with an open ended slot 35 for the reception of the button shank, and said plates being superimposed with the open ended slots therein extending in opposite directions and with the button shank lying in said slots, opposite sides of each of said slots 40 being provided with a slot for receiving the ridge on the button shank.

7. In a hose supporter structure, the combination of a button comprising a head, a shank and a base, a two-section base plate 45 each section of which is provided with an open ended slot extending to the end of the plate, said plates being superimposed with said slots in register but extending in opposed directions with the button shank lying 50 therein, the open end of the slot in one section being closed by the material at the closed end of the other section.

8. In a hose supporter structure, the combination of a button comprising a head, a shank and a base, a two-section base plate, each of said sections being provided with an open ended slot cut through the side thereof for receiving said button shank, said plates being superimposed with said slots 55 60 in register and with the button shank received thereby and with the open end of the slot in one section closed by the material at the closed end of the other section.

This specification signed this 31st day of 65 August, 1926.

CARL J. HAZELTON.
